AUTOMOBILE DOOR HANDLE

Donald C. Lindenmuth, Utica, Mich., assignor to General Motors Corporation, Detroit, Mich., a corporation of Delaware

Application October 3, 1958, Serial No. 52,864

Term of patent 7 years

(Cl. D10—8)

Fig. 1 is a top plan view of an automobile door handle incorporating my new design;

Fig. 2 is a side elevational view of the automobile door handle;

Fig. 3 is an end elevational view looking from the left of Fig. 2;

Fig. 4 is a section through a portion of the door handle taken along the line 4—4 of Fig. 1;

Fig. 5 is a section through a portion of the door handle taken along the line 5—5 of Fig. 1; and

Fig. 6 is a section through a portion of the door handle taken along the line 6—6 of Fig. 1.

The dominant features of my design are shown in the full line portions of the drawing.

I claim:

The ornamental design for an automobile door handle, substantially as shown and described.
